INVENTOR,

Morris Sellers,
BY *George H. Christy*
ATTORNEY.

UNITED STATES PATENT OFFICE.

MORRIS SELLERS, OF CHICAGO, ILLINOIS.

RAILWAY SPLICE-BAR.

SPECIFICATION forming part of Letters Patent No. 339,940, dated April 13, 1886.

Application filed November 21, 1885. Serial No. 183,464. (No model.)

To all whom it may concern:

Be it known that I, MORRIS SELLERS, residing at Chicago, in the county of Cook and State of Illinois, a citizen of the United States, have 5 invented or discovered a certain new and useful Improvement in Railway Splice-Bars, of which improvement the following is a specification.

In the accompanying drawings, which make 10 part of this specification, Figure 1 is a side view or elevation of a railway-track joint taken from the inside and illustrative of my present invention. Fig. 2 is a like view taken from the other or outer side. Fig. 3 is a horizontal sectional view through the plane of the 15 bolt-holes. Fig. 4 is a vertical cross-section in the plane of the line $x-x$, and Fig. 5 is a like view in the plane of the line $y-y$. Fig. 6 is a transverse sectional view of a modification of 20 my improved splice-bar.

My invention relates to an improvement in the splice-bars commonly used as splicing-pieces in railway-track joints, with reference 25 to securing a maximum of rigidity immediately at the joint, or where the rail ends abut, along with a progressive or increasing degree or amount of flexibility or "yield" in the splice-bar, thence each way to its ends, the result sought for being to secure as nearly as may be an 30 amount of deflection at the joint which shall be the same, or approximately the same, as exists elsewhere in the rail, or, in other words, to secure a constant and uniform wave of deflection 35 continuously along each line of rails under the action of a passing train as well at the joint as along the body of the rail away from the joint. To insure this result a considerable amount or body of metal should be put into the fish or splice bars immediately 40 at the joint; but as the capacity or liability of the rail to yield or give downward under a passing load decreases rapidly as we recede from the end, and for a foot and a half or two feet decreases with practical uniformity until 45 at or about that point it becomes constant or normal throughout the rest of the length of the rail, from this it necessarily follows that the rigidity of the splice or fish bars should decrease uniformly, or approximately so, from 50 the thick or comparatively rigid middle portion toward each end. Hence in order to secure this and get a practically uniform yield or

deflection at as well as away from the joint, along with a continuous and practically uniform wave of deflection along the entire line 55 of rails, I make the splice-bars with a comparatively thick middle portion and tapering therefrom in thickness each way to or toward the end, but preserving a uniform width or height from end to end with suitable shape 60 and proportion, whereby the top and bottom edges of each splice-bar will take a firm bearing or seat on the under side of the head of the rail and on top of the flange throughout the entire length of the bar, but without coming into binding contact with the web. Then 65 it will be seen that as the rail loses in rigidity toward its extreme end, and thereby would be liable to too great deflection, the splice-bars applied thereto increase in rigidity approximately in corresponding degree or amount; but, being made of wrought metal, 70 they still have a certain amount or degree of flexibility or capacity to yield, such that the deflection of the rail at and near the joints 75 will be the same or approximately the same as it is in the body of the rail remote from the joint; and in order to secure this uniform action it is important, and in fact essential, that the splice-bars be made of wrought metal— 80 say steel or wrought-iron—since a cast-iron splice-bar has too little flexibility or capacity to yield to be adapted for the use desired, and as the operation of rolling is the only way 85 such wrought splice-bars can be produced with commercial success, I limit myself to one which is capable of being produced by the operation of rolling as ordinarily practiced in metal-working.

In the drawings, A A represent the abutting 90 ends of two track-rails, and B B' represent the splice-bars or fish-bars of what is technically known as a "combination-joint," in which the inside bar, B, is so made that its upper and lower edges bear on the under side of the rail-head and on the upper side of the flange, while the outer bar, B', is so formed and shaped as to have like seats or bearings, and has also a flange, b, which projects outwardly any desired distance down the upper face of the flange, 95 and, if so preferred, sufficiently far to rest on the cross-ties; but in so far as relates to the present invention both of the bars may be made like B or both like B'. These splice or fish

bars are produced by the ordinary rolling operation, from steel or wrought-iron, in single sections or continuous lengths and afterward severed, as may be preferred; but each bar has this characteristic, that it is rolled with a middle portion, *a*, comparatively thick and heavy with reference to supporting the rail ends as against any downward deflection materially greater than the rail receives at its middle portion, and also with reference to carrying the wave of deflection progressively and regularly forward from the end of one rail into the abutting end of the next rail, so as to avoid an injurious jar in the passing train, or a destructive or injurious blow of the wheel on the rail end, or a serious or breaking strain on the rail; and that the flexibility properly belonging to the rails at their middle portions, and thus secured immediately at their ends, may be preserved as near as may be constant in degree or amount along the lapping lengths of the splice-bars, I make the latter with a practically uniform taper in thickness, but not in width, from at or near the middle parts, *a*, thereof to the extreme ends, and by virtue of the existence of this taper their rigidity is progressively lessened toward their ends correspondingly as the rigidity of the rail through the same distance is increased. At the same time this rigidity is not absolute, either in the rail or splice-bars; but by the taper described and indicated I give to them such relative amount or degree of flexibility as will result in a practically uniform deflection in all parts of the track, and the propagation of the wave of deflection through the joints from rail to rail and along the rails without serious break or jar; and it will be observed that the inner faces of the bars are so shaped relatively to their width that the bars do not take a binding engagement on the web, and hence as the edges wear away in use they may be drawn in or set up to the rails by the use of the ordinary bolts and nuts, as illustrated in the drawings.

As a modification of the taper bar described, I prefer in some cases to taper only the body of the bar, leaving the upper and lower edges of full thickness, as illustrated in Fig. 6, where the full lines represent the end of the bar, and the dotted line *s* represents the exterior line of the bar at its thick middle portion. In this case the taper is practically uniform from the thick middle portion to its ends, along the body *c*, between the upper and lower beads, *c* *c*²; but the latter preserve substantially the full width of upper and lower bearing-surfaces throughout, so as to wear away with practical uniformity from end to end.

I am aware that splice-bars alternately thick and thin at different portions of their length have been made with reference to the attainment, so far as could be done in that way, of the useful results above referred to, as in Patent No. 170,384; but the alternating of thick and thin portions, as therein described, tends to interfere to that extent with

the uniformly progressive increase of rigidity in the splice-bar which is desired, whereby a practically constant deflection is secured continuously along the track-rails.

Without limiting myself to any exact dimensions or proportions, I would add that on a thirty-six-inch bar, with the most commonly used standard or pattern of American rail, I believe that good results can be secured by a seven-eighths-inch thickness in the bar at its middle portion, a one-half-inch thickness at each end, and a practically uniform taper between those points, with the usual spacing and number of bolt-holes.

Heretofore the efforts of most inventors in this branch of the arts have been directed to making the rail-joints as rigid as possible, and in doing so they have utterly ignored, or else were ignorant of, the fact that excessive rigidity at the joint is as fatal a defect as excessive flexibility.

The present invention is directed to the securing of a degree or amount of flexibility at the joint corresponding as near as may be to the flexibility of the rail at its middle part or away from the joint, and also to making that flexibility uniform or constant throughout or continuously along the rail and joint. I do not claim, broadly, that tapering splice-bars are new with me, such being found in English Patent No. 1,780 of 1853, and in United States Patents No. 304,895, of September 9, 1884, No. 215,509, of May 20, 1879, No. 251,030, of December 20, 1881, and perhaps in others; but in all these cases wedge-like-acting clamping-chairs are employed or combined therewith in such manner as to exclude the desired flexibility at the joint, or to prevent the wave of deflection which necessarily exists in the rail from moving forward through the joint without material change or interruption, and this will be the more apparent when it is observed that in all the patents last cited the splice-bars are too short and too thick to provide in any event for any appreciable amount of vertical deflection; hence it will be understood that I disclaim the taper splice-bar when combined with clamping-chairs operating thereon by a wedge-like action. The interiorly-tapered splice-bar of United States Patent No. 234,529, of November 16, 1880, is also disclaimed, as not attaining the results I have in view, for the reason that the metal at and toward the ends of the bars is so disposed in relation to the web as to act on the principle of the arch, and so interfere with or prevent the uniform movement of the wave of deflection through the joint; and it will also be understood that the stepped or re-enforced form of splice-bar shown in the Long patent, No. 170,384, of November 23, 1875, and in my own patent, No. 285,688, of September 25, 1883, is not included as within the invention herein claimed.

I claim herein as my invention—

1. A pair of elastic wrought-metal splice-bars of or approximately of standard length,

each comparatively thick at its middle portion, and having its outer walls tapering therefrom to its ends, and each having suitably-shaped edges for taking a continuous bearing or seat on the under side of the rail-head and on the flange, in combination with the abutting rail ends of a railway-track, and with a bolt-and-nut fastening, as shown and described, with reference to securing a practically uniform flexibility and a continuous wave of deflection in all parts of the track, substantially as set forth.

2. An elastic wrought splice-bar having a

comparatively thick middle portion and its outer wall tapering therefrom in its body portion each way to its ends, and having its inner wall straight, and having upper and lower bearing-edges of uniform thickness from end to end, and provided with suitably-spaced bolt-holes, substantially as set forth. 15 20

In testimony whereof I have hereunto set my hand.

MORRIS SELLERS.
